UNITED STATES PATENT OFFICE.

LOUIS E. LADD, OF PROVIDENCE, RHODE ISLAND.

AUTOMATICALLY-ADJUSTABLE DEVICE.

1,264,530.

Specification of Letters Patent. Patented Apr. 30, 1918.

Application filed January 14, 1918. Serial No. 211,767.

To all whom it may concern:

Be it known that I, LOUIS E. LADD, a citizen of the United States, and resident of the city of Providence, in the county of Providence and State of Rhode Island, have invented certain new and useful Improvements in Automatically-Adjustable Devices, of which the following is a specification.

This invention relates to a spring-actuated, automatically-adjustable device adapted to serve as a yielding extendible member for use on band bracelets, garters, belts, suspenders or for any other purpose for which the device may be adapted.

The object of this invention is to provide a mechanical device adapted to yield under spring tension when pressure is brought to bear thereon and to return to normal position when the pressure is released.

With these and other objects in view, the invention consists of certain novel features of construction, as will be more fully described, and particularly pointed out in the appended claims.

In the accompanying drawings:

Figure 1—is a perspective view showing a pair of my adjustable devices connected to operate as an extension member on a band form of watch bracelet.

Fig. 2—is a plan view of a pair of rack-plates arranged to be hinged together.

Fig. 3—is an enlarged sectional view on line 3—3 of Fig. 2, showing the teeth of the rack-plate as being swaged into the plate.

Fig. 4—is a central longitudinal section through the gear member of the device.

Fig. 5—is an end view of the gear showing the same as engaging the teeth of the rack partly in section; also showing the housing in section.

Fig. 6—is a section through the housing on line 6—6 of Fig. 8, showing the square hole in its end wall for receiving the correspondingly-shaped end of the shaft.

Fig. 7—is a perspective view of the shaft, showing one end as being square to fit the correspondingly-shaped hole in the wall of the housing and the other end as being split to receive the end of the tension spring.

Fig. 8—is a section through the gear, the rack and the housing, showing the whole as assembled.

Referring to the drawings, 10 designates a rack-plate which may be made in one piece, or it may be made in halves if desired and the halves hinged or otherwise

connected together as at 11, as shown in Fig. 2, so that two oppositely-disposed, yielding members may be mounted thereon when required.

These rack-plates may be formed of any suitable material but are preferably formed of a sheet of metal having teeth 12 swaged or depressed thereinto, as illustrated in Fig. 3, along the middle portion of the plate, 65 leaving the outer margins 13 plain, smooth or unswaged so as to provide guides on which the flanges of the housing slide.

This housing member or carriage 14 is preferably formed in a trough-shape having end walls 15 and 16. The end wall 15 being provided with a square opening as at 17, to receive the correspondingly-shaped end 18 of the shaft 19, the hole 20 in the opposite wall 16 being round, to receive the 75 opposite end of the shaft. Each of these walls is provided with a downwardly and inwardly turned projecting flange 21 which is designed to extend under the plain edge 13 of the rack-plate for the purpose of retaining the housing in sliding engagement 80 with said plate.

I have also provided a gear 22 having teeth 23 which engage those of the rack, the center portion of this gear being hollow 85 as at 24 and provided with end bearing members 25 and 26.

A tubular shaft 27 extends longitudinally through this chamber 24 and through these bearing members, the square end of this 90 shaft passing through the square hole 18 of the housing while the opposite end of the shaft is split as at 28 and passes through the wall 16 of the housing. These opposite ends are both spread and riveted over the walls 95 15 and 16, respectively, of the housing, to bind the shaft in position therein.

In order to permit the necessary yielding and rolling action to this gear, I have mounted a torsional, helically-disposed 100 spring 29 about its shaft 27, one end 30 of the spring being secured in the bearing-head 25 of the gear while the opposite end 31 of the spring is passed through the slot 28 in the shaft, whereby when the housing 105 is drawn outwardly or caused to be moved along the rack from its position, it winds up or tightens this spring, causing it to act upon the housing and gear to return them again to normal as soon as released.

When my improved adjustable device is employed as a yieldable member for band

bracelets and the like I preferably form a loop-member 32 on the lower edge of each housing, and to each of these is secured an end 34 of the band members 33, the same being led out through the guide loops 35 on the outer ends of the rack-plates, the opposite ends of the band sections being connected as at 36 to the bracelet watch 37.

Of course when used as a garter the watch 10 is omitted.

In some instances where but a single yieldable gear element is desired, one end of the band would be connected to the housing and the opposite end at the joint 11 of the rack 15 plate.

My improved automatically adjustable device is a purely mechanical construction designed to be applied as an elastic means in any place, and is often used in places where 20 it is adapted to perform the yieldable function of elastic webbing such for instance as in belts, suspenders, bracelets and the like for personal wear, but I do not restrict myself to the use of this device for such purposes as the same may be used for any purpose where such a yieldable and adjustable device is adapted to be applied.

The foregoing description is directed solely toward the construction illustrated, 30 but I desire it to be understood that I reserve the privilege of resorting to all the mechanical changes to which the device is susceptible, the invention being defined and limited only by the terms of the appended claims.

35 I claim:

1. As an article of manufacture, an automatically adjustable device comprising a rack-plate, and a spring-actuated gear meshing with said rack adapted to automatically return to normal position after having been moved along the rack.

40 2. A new article of manufacture comprising-

Copies of this patent may be obtained for five cents each, by addressing the "Commissioner of Patents, Washington, D. C."

ing a rack plate, a housing slidably engaging said plate, a gear engaging said rack and rotatably mounted in said housing, a member connected to said housing, and means for returning said gear and housing to normal position when moved therefrom along said rack by tension on said member. 45

3. A new article of manufacture comprising a rack plate, a gear meshing with said plate, a member in which said gear is rotatably mounted slidably engaging said plate, and a torsional spring acting upon said gear to return the same to normal position after 50 having been rolled along said rack.

4. A new article of manufacture comprising a rack plate, a gear meshing with said plate to roll thereon, a housing slidably mounted on said plate and in which said 55 gear is rotatably mounted, a torsional spring mounted in said gear to rotate it, and a tension member connected to said housing to move it with the gear along the rack to wind up said spring whereby said housing is returned to normal position when the tension is released. 65

5. A new article of manufacture comprising a rack-plate, a pair of oppositely-disposed housing members slidably mounted on said plate, a gear mounted in each housing and engaging said rack, a spring acting upon each to rotate in opposite directions, and a tension member for moving said housings apart whereby the springs in each is placed under increased tension to return said 70 housings to normal when the tension is released. 75

In testimony whereof I affix my signature in presence of two witnesses.

LOUIS E. LADD.
